UNITED STATES PATENT OFFICE.

JOHN H. FONES, OF OAKLAND, CALIFORNIA.

WRENCH.

Application filed October 6, 1924. Serial No. 742,022.

To all whom it may concern:

Be it known that I, JOHN H. FONES, a citizen of the United States, and a resident of Oakland, in the county of Alameda and

5 State of California, have invented a new and Improved Wrench, of which the following is a full, clear, and exact description.

This invention relates to wrenches and more particularly to a wrench which may 10 be used for nuts or bolts or for a pipe wrench by the employment of a simple attachment.

An object of the invention is to provide improved mounting for the adjusting worm 15 which ensures proper engagement of the worm with the rack bar of the wrench but which enables a quick release of the worm from the rack bar when a quick adjustment is desired.

20 This invention has specifically to do with the mounting of the worm for adjusting the rack and requires a longitudinal as well as a lateral movement of the worm to release it from interlocking engagement with the 25 rack.

With these and other objects in view, the invention consists in certain novel features of construction and combinations and arrangements of parts which will be more 30 fully hereinafter described and pointed out in the claims.

In the accompanying drawings—

Figure 1 is a view in elevation, partly 35 in section, illustrating my improved wrench;

Fig. 2 is a view in transverse section on the line 2—2 of Fig. 1; and

Fig. 3 is a view in transverse section on the line 3—3 of Fig. 1.

40 1 and 2 represent the jaws of the wrench. The jaw 1 is formed integral with the shank 3 which is provided on one edge with teeth 7. The jaw 2 is preferably an integral part of a sleeve 4 mounted to slide on the 45 rack bar so as to permit adjustment of the jaws relative to each other. The sleeve 4 is made with a cut-out portion 5 to accommodate a worm 6 which is normally in mesh with the teeth 7 of rack bar 3. This worm 50 6 is hollow or of tubular form and mounted to turn upon a rod 8, the ends of the rod being mounted in longitudinal recesses or bores 9 and 10 in the respective end walls of the cut-out portion 5. This rod 8 is 55 of general cylindrical form with the end portions thereof recessed or cut away so

that the extremities of the rod in the respective recesses 9 and 10 are semicylindrical in form or less than a semicircle so as to allow the rod to move laterally. 60

To hold the rod 8 in normal position coil springs 10' are located in the recesses and preferably seated in sockets 11 in the rod. This rod 8 is secured in operative position and held against longitudinal movement by 65 means of a pin 12 which is projected through a portion of the sleeve and through the rod, as indicated clearly in Figure 1. It is to be understood, however, that this pin 12 permits a lateral movement of the 70 rod 8 as will more fully hereinafter appear.

To facilitate the assemblage of parts, I preferably provide a plug 23 closing an opening 24 in the sleeve 4, through which opening the spring 10' can be inserted or 75 removed. This plug 23 I fix by means of a cross pin 25 projected through the metal of the jaw.

The cutout portion 5 of the sleeve 4 is 80 appreciably longer than the worm 6 so that the latter is permitted a longitudinal movement on the rod 8. One end of this worm 6 is made with a circular enlargement 13 which fits in a curved recess 14 in one end wall of the cutout portion 5; and a coil 85 spring 15 is located around the rod 8, the worm 6 and the other end of the cutout portion 5 to hold the enlargement 13 normally in the recess 14 and thus prevent 90 any accidental lateral movement of the worm.

The parts are positioned as above described for normal operation and when it is desired to quickly adjust the wrench it is necessary first to grasp the worm 6 and then exert pressure on the jaw 2, forcing the same toward the jaw 1. As the worm 6 and the rack-bar 3 are locked together by reason of their engagement, the sleeve 4, as a whole, will be moved toward the jaw 1 a distance sufficient to release the worm 100 from its interlocking engagement with the forward wall of the cutout portion 5, and when in this position the worm and the rod 8 supporting the same can be moved laterally to disengage the worm from the rack teeth 7 and allow the jaws to be quickly 105 adjusted. When the worm is released the springs 15 and 10' will return the worm to its normal position in engagement with 110 the rack bar.

In order to change the wrench from an

ordinary bolt head or nut wrench into a pipe wrench, I employ a removable block 16 which fits against the jaw 1 and against the edge of rack bar 3 and is provided with an inclined series of beveled teeth 17. This block carries a dowel pin 18 which projects into a recess 19 in the jaw 1 and is also provided with a spring-pressed plate 20 adapted to straddle the edge of the rack bar and to hold the block against lateral movement. When this block 16 is not desired for use it may be inserted in a receptacle 21 in one end of the bar 3 and held by a removable cap 22.

15 Various slight changes and alterations might be made in the general form of the parts described without departing from my invention, and hence I do not limit myself to the precise details set forth but consider myself at liberty to make such slight changes and alterations as fairly fall within the spirit and scope of the appended claims.

I claim:

1. A wrench, comprising a pair of jaws, a rack-bar fixed to one jaw, a sleeve carrying the other jaw and receiving the rack-bar, said sleeve having a cutout portion therein and having longitudinal recesses in the end walls of the cutout portion, a worm in the cutout portion normally engaging the rack-bar, a rod projecting through the worm, mounted in the recesses and having lateral movement in the recesses, springs in the recesses engaging both ends of the rod and holding the worm in normal engagement with the rack-bar, said worm having interlocking engagement with one wall of the cutout portion, whereby longitudinal as well as lateral movement of the worm is required to release it from engagement with the rack and a spring normally pressing said worm into its interlocking position.

2. A wrench comprising a pair of jaws, a rack-bar fixed to one jaw, a sleeve carrying the other jaw and receiving the rack-bar, said sleeve having a cutout portion therein and having longitudinal recesses in the end walls of the cutout portion, a worm in the cutout portion normally engaging the rack-

bar, a rod projecting through the worm, mounted in the recesses and having lateral movement in the recesses, springs in the recesses engaging the rod and holding the worm in normal engagement with the rack-bar, said worm having a circular enlargement at one end, said sleeve having a circular recess in one wall of the cutout portion receiving said enlargement and holding the worm against lateral movement, and a spring exerting longitudinal pressure on the worm and normally holding said enlargement in the recess.

3. A wrench comprising a pair of jaws, a rack-bar fixed to one jaw, a sleeve carrying the other jaw and receiving the rack-bar, said sleeve having a cutout portion, a rod mounted in the sleeve and extending across the cutout portion, said rod capable of lateral movement, elastic means holding the rod against lateral movement, a pin projecting through the rod and mounted in the sleeve and holding the rod against longitudinal movement, a worm on the rod engaging the teeth of the rack, a spring exerting pressure on the worm, and interlocking means between one end of the worm and one wall of the cutout portion whereby longitudinal as well as lateral movement of the worm is required to release it from engagement with the rack.

4. A wrench comprising a pair of jaws, a rack fixed to one jaw, a member mounted to slide on the rack, a jaw on said last-mentioned member, a worm carried by the said member and normally engaging the rack, said worm having an annular integral enlargement at one end, said member having a recess receiving said enlargement and holding the worm against lateral displacement, a spring engaging the end of the worm and holding its enlargement in the recess, and means permitting the lateral movement of the worm away from the rack when the worm is moved longitudinally to remove its enlargement from the recess in the member.

JOHN H. FONES.
